CLAIM

The ornamental design for a curved wheel leveler and chock set, as shown and described.

DESCRIPTION

FIG. 1 is a right, front perspective view of a curved wheel leveler and chock set showing our new design;
FIG. 2 is a left, rear perspective view thereof;
FIG. 3 is a front view thereof;
FIG. 4 is a rear view thereof;
FIG. 5 is a left view thereof;
FIG. 6 is a right view thereof;
FIG. 7 is a top view thereof;
FIG. 8 is a bottom view thereof; and,
FIG. 9 is a partially enlarged view of FIG. 4

The broken lines shown on the drawings depict portions of the curved wheel leveler and chock set that form no part of the claimed design.

The broken line boundary shown in FIGS. 4 and 9 is used only to call out a portion of the design for a magnified partial view, but the broken line boundary itself forms no part of the claimed design.
